EYE SHIELD FOR A GAS MASK OR SIMILAR APPARATUS

Guy G. Klinger, Shillington, Pa., assignor to The Electric Storage Battery Company, Philadelphia, Pa.

Filed Dec. 24, 1963, Ser. No. 77,918

Term of patent 14 years

(Cl. D83—1)

Fig.1.

Fig.2.

Fig.3.

FIG. 1 is a perspective view of an eye shield for a gas mask or similar apparatus showing my new design, where-in the dot and dash outline of a gas mask is for illustrative purposes only;

FIG. 2 is a top view thereof; and,

FIG. 3 is an enlarged, cross-sectional view thereof.

The view taken on the opposite side of FIG. 1 is the same.

I claim:

The ornamental design for an eye shield for a gas mask or similar apparatus, substantially as shown and described.
